UNITED STATES PATENT OFFICE

WILLIAM L. SMITH, JR., OF NASHVILLE, TENNESSEE, ASSIGNOR TO MAY HOSIERY MILLS, OF NASHVILLE, TENNESSEE, A CORPORATION OF TENNESSEE

KNITTING MACHINE

Application filed October 28, 1925. Serial No. 65,426.

My said invention relates to a knitting machine and it is an object of the same to provide a circular machine of the type having a revolving needle cylinder with means whereby stockings can be made thereon having ribbed tops with plain feet provided with heel and toe pockets or pouches in usual manner, the whole being knitted from toe to top in one continuous piece. It will be understood that the invention is not limited in all respects to a machine having a revolving needle cylinder as some of the parts may be used with machines having a stationary needle cylinder and revolving needle cams.

Neither is it limited to the forming of stockings as other fabrics may be formed thereon.

Another object is to provide improved cams for operating a series of dial needles.

Another object is to provide an improved pattern mechanism for controlling said cams.

Another object is to provide an improved take-up for a machine capable of making the fabric described.

Referring to the accompanying drawings, which are made a part hereof and on which similar reference characters indicate similar parts,

Figure 1 is a front elevation of the machine of my invention,

Figure 2, a rear elevation of a part of the machine on an enlarged scale,

Figure 3, a plan of the upper part of the machine,

Figure 4, a development of the cams for actuating the cylinder needles,

Figure 5, an elevation of the pattern mechanism viewed from the right in Figure 1,

Fig. 5a, a detail of certain parts shown in Fig. 5, but at right angles to said figure,

Figure 6, a similar elevation of a part of said mechanism on an enlarged scale,

Figure 20, a modified yarn-pusher.

Supporting and driving connections

The general construction of the machine is similar to that of the well-known Banner machine as shown in the patent to Hemphill, No. 933,443, September 7, 1909, said construction including a revolving needle cylinder 25 and a stationary support 26 on which are mounted a sliding block 27 carrying cams for the cylinder needles 27' (Fig. 4), the pickers of which one is indicated at 28, the instep cams 29, and various other parts of the mechanism.

A bracket 30 is mounted on the support 26, said bracket extending over the cylinder and being provided at its outer end with an aperture through which passes the dial post 32.

A gear 33 is secured to the sinker bed outside of and just below the sinker cam ring 25'. A similar gear 34 is secured to the upper end of the dial post by means of a nut 35 said gear resting on a flange 36 of the post which flange rests on the bracket 30. As shown in Fig. 3 the web of the gear is cut out to reduce its weight or it may be solid if preferred.

A shaft 37 (Fig. 2) is journaled in a bearing supported by the bracket 30 and said shaft carries bevel gears 38 and 39 the teeth of which mesh respectively with the teeth of gears 34 and 33 thus driving the dial in synchronism with the needle cylinder. The dial post is mounted to rotate in a sleeve 40 fixedly supported at the end of the bracket 30. A plate 41 is preferably formed in one piece with the

55

60

70

75

80

85

90

95

sleeve 40 said plate having a cam slot in which a follower 42 (Fig. 18) is movably mounted. The plate 41 is here shown as being approximately on a level with the top of the latch ring 43.

The dial 44 is secured to the lower end of the dial post in any convenient manner. Above the dial is a dial cam cap 45 shown in detail in Figures 13 to 16 and above this is a plate 10 46, preferably annular, which is substantially stationary but may have a slight oscillatory movement, the extent of which is determined by means of a set screw 47 engaging the pin 48 on the plate 46 extending upward through 15 a slot in the plate 41 (Fig. 3). Preferably a lost motion connection is provided between the plate and the plate 41 as this is found to prevent cramping of the parts on the plate and their connections.

20 The cylinder is driven as usual by a gear 49 on a shaft driven from a belt 50 through a set of pulleys 51, 52, 53, gearing 54 being interposed as usual for causing the gear 49 and the needle cylinder to rotate or oscillate 25 in well-known manner. In my invention obviously the dial will have movements similar to those of the cylinder.

Dial cams and controlling mechanism therefor

30 At its underside the dial cam cap is provided with an outer wall or rib 55 (Fig. 13) combining in itself guard cams and needle retracting cams 57 and 58. The knocking over point of the needle retracting portion is at 56. The outer wall of the needle-butt path is interrupted at one point by a gap closed by a gate 59 which gate is slidable in a 35 counterclockwise direction in Figure 17 to open the gap and permit the removal of the dial needles 59' (Fig. 13). A spring 60 serves to return the gate to closed position. The inner wall of the needle butt path is formed by a downward projection 61 of the cam cap 45 which projection is reduced at one side to provide space for an oscillatory needle projecting cam 62 pivoted at 63. The oscillation of the cam is brought about by movement of the dial cam cap about the dial post as an axis 40 whereupon the needle projecting cam is moved in and out by the cam path in the plate 41 in which path the follower 42 travels. The cam cap has an upwardly projecting circular portion 64 (Fig. 2) which engages 45 the inner periphery of the plate 46 and aids in holding the parts in place.

The oscillation of the cam cap for adjusting the needle projecting cam to its various positions is effected by a train of mechanism 50 including a link 65 pivotally connected to the dial cam cap and to a rod 66 slidably supported in a bearing 67 mounted at one side of the bracket 30. The bearing has a lateral extension 68 with a slot at one side in 55 which is guided a pin 69 extending into a slot

in a rockarm 70 (Figs. 1 and 3). The rockarm is fixed to a rockshaft 71 journaled in a sleeve 72. The rockshaft at its other end is provided with a gear 73 having a set of teeth, which teeth mesh with teeth of an internal gear 74 arranged about an arc of approximately 180°, said gear being mounted for oscillatory movement on the outer end of the shaft 71 that is provided for this purpose with an eccentric flange 75. A link 76 is pivotally secured to the gear 74 at its upper end and at its lower end is pivoted to a lever 77 (Fig. 5) arranged for actuation by lugs on a pattern chain 78 positioned to engage with a laterally extending pin 79 at the free end of the lever.

The pattern chain passes over an independently rotatable sprocket 80 which sprocket is driven by a ratchet 81. A pawl 82 is mounted as usual on the oscillating quadrant which causes the machine to knit reciprocatingly and said pawl normally moves the ratchet one step for four rotations of the needle cylinder. At certain times a higher speed is desirable, such as one step for each revolution of the needle cylinder.

55 I have provided means for speeding up the movement of the chain at certain times, which means, however, cannot be used throughout the knitting of the entire stocking as it would interfere with the proper operation of the machine in knitting heels and toes, and a very long chain would be required.

60 For the purpose of speeding up the movement of the chain at certain times another pawl indicated at 83 is arranged for engagement with the ratchet, this pawl being constantly operated by an eccentric 84 on which the pawl is pivotally supported. The eccentric is driven by a gear 85 with which it may be integral which gear is driven from a series of gears 86, 87, 88, the latter being the quadrant driving gear of the Banner knitting machine.

65 The pawl 83 is normally held out of action by gravity and an elevator 89 engages the underside of the pawl for lifting it into engagement with the ratchet, the elevator being pivotally mounted and pressed upward by a spring 90. When this is done the ratchet will be driven a step for each rotation of the needle cylinder, the pawl being moved at this rate by the gearing indicated. The elevator 89 is moved downward on its pivot 90' by an eccentric portion 93 of a shaft 92 shown in detail in Figures 7 and 8. The shaft has another eccentric portion at 91 passing through a slot in a lever 94 pivoted at 95 (Fig. 5). At its forward end the lever is connected by a pin and slot connection to a vertically slideable rod 96 (Figs. 5 and 5a) provided at its upper end with a finger 96' acted on by a spring 97' said finger engaging the underside of the pawl 82. The purpose of this yielding action of spring 97' is to prevent damage to

70

125

130

the mechanism should the rod 96 be lifted while the pawl is being moved forward and is pressing against a ratchet tooth in which case the finger can yield until the pawl is released from the ratchet whereupon the pawl will be lifted.

The shaft 92 is journaled in a support mounted on a fixed part of the machine frame and is rotatable by means of a gear 97 provided with an integral sleeve extending into a ratchet drum 98 fixed to the shaft by a set screw 98'. A pawl 100 (Fig. 9) is pivoted in a circumferential notch on the ratchet drum said pawl being impelled by a spring 101 in a direction to engage with notches at 102 in the sleeve portion of the gear 97. A leaf spring 103 has a bent end for engagement in notches in the ratchet drum for holding it in place after it has been driven through a half rotation by the shaft 92 acting through the ratchet clutch.

The rack segment 99 (Fig. 6) is pivoted on a fixed support and is connected by a link 104 to a lever 105, pivoted at 106, and carrying a pin at 107 engaging a slot in a lever 108. The lever 108 is positioned for engagement at its free end by a lug 109 on the chain 78. A spring 110 serves to hold the lever normally in the position of Figure 6.

In the operation of the chain driving means the parts are normally in the opposite position to that indicated in Figure 5 with the pawl 82 engaging the ratchet 81 and driving the chain one step to four rotations of the needle cylinder and dial. When it becomes desirable to speed up the operation of the chain, as during the transfer from plain to rib knitting, in casting off or in making a welt a lug 109 on the chain engages the adjacent end of the lever 108. The surface at the upper side of the short portion of the curved slot in said lever now bears down on the pin 107 of the lever 105 and by the movement of this lever about its pivot 106 acts through the link 104 and quadrant 99 to turn the gear 97 and rotate the shaft 92 through an arc of 180°. This brings the eccentrics 91 and 93 into the position shown in Figures 5, 6 and 8. The eccentric 91 acts on lever 94 to lift the rod 96 and pawl 82 into the position shown in Figure 5.

At the same time the eccentric portion 93 has been moved upward to relieve its pressure on the elevator 89 which is now moved upward by its spring 90 and carries the pawl 83 into engagement with the ratchet whereupon the ratchet 81, sprocket 80 and chain are moved one step for each revolution of the needle cylinder and dial. This action continues until the lug 109 on the chain passes the free end of lever 108 whereupon the operation just described is reversed and the pawl 82 is returned to action. When the pawl 82 returns to action the chain is again moved

once for each four revolutions of the cylinder.

It will be understood that after the lug 109 passes the lever 108 the parts return to the position indicated in Figure 6, the gear 97 being permitted to turn freely backward on the shaft by means of the ratchet clutch.

A locking or latching device is provided for holding the dial cam cap in a position which corresponds to the idle position of the dial needle cam 62 (Figs. 2 and 3). This locking means comprises a rocker 111 having a triangular lug 112 at one side thereof. This lug is adapted to engage in a notch at 113' on a fixed abutment 113 of approximately elliptical shape having both ends pointed. Such engagement occurs on movement of the rock-arm 70 to the left in Figure 2 by a lug on the pattern chain 78 through levers and connections between the said chain 78 and a rock arm 70.

To release the latch it is moved further to the left as by a higher lug on chain 78 and descends under the influence of gravity plus the action of the cam at 113" below the level of abutment 113 whereupon the lug 112 strikes the upper surface of a lever 114 pivoted at 115 and supported in the position indicated by a coil spring 115' connected at one end to a pin 116 on the lever which pin extends through a slot in the rearmost one of a pair of plates 117 between which the rocker 111 and lever 114 are guided for up and down movement. At its upper end the spring is attached to a suitable holding means at the farther side of the rear one of the plates 117.

It will be seen that the lever 114 will support the lug 112 which when the rockarm 70 moves to the right will ride underneath the abutment 113 under the tension of the spring 115' after which the rocker 111 will rise and lift the lug 112 into the position shown in Fig. 2. When the rockarm now moves to the left in said figure the lug will readily ride over the abutment 113. When the locking means is released the rod 66 will be moved to the right in Figure 2 by a spring 118 to the limit of its movement in that direction.

When the cam follower 42 reaches the end of the cam slot indicated by the reference letter *a*, Figure 18, the dial cam is in the locked position and is thereby prevented from being moved to a projected position. It should be noted that pattern chain 78 moves continuously although intermittently and when a lug thereon moves by, the locking device functions, i. e., when a pattern chain lug is not operative the latch serves the purpose intended.

The cams for operating the cylinder needles are shown in detail in Figure 4 and comprise a bottom center cam 119, a top center cam 120, stitch cams 121 and 122, a needle raising cam 123 and a guard cam 124 above the same. The top and bottom center cams and the stitch cams shown at the right in Fig-

ure 4 may be as in the prior art but stitch cam 122 has an extended horizontal portion at 125 for holding down the cylinder needles until the dial needles have drawn their loops. The needle raising cam 126 is, of course, similarly formed so as to provide a narrow path for the needle butts.

The machine of my invention is provided with sinkers whereas the ordinary ribber does not have sinkers. By reason of the presence of the sinkers the fabric cannot pass down to the take-up in the same direct manner from my machine as is the case in conventional ribbers. Cam 123 is therefore provided for lifting the needles to a greater height than would be necessary in plain knitting or even in a conventional ribber. It will be understood that the level of the verge of the forming fabric is raised during rib knitting since while knitting plain fabric the position of this verge is determined by the sinkers or in other words the work is held by the throats of the sinkers whereas in rib knitting the dial needles necessarily pull the fabric upward to a certain extent, away from the throats of the sinkers.

It is important also that the needles be not so high during reciprocating knitting when the cylinder needles alone are in operation as to fail to engage the pickers, or as to engage at improper times and damage the machine. The cam 124 finds its usefulness during the reciprocating part of plain knitting when the low place at the left-hand side in Figure 4 can bring the needles down to prevent their butts from striking the droppers while the up-picks are acting to narrow the fabric and locate the butts properly for engagement by said up-picks. During the above widening and narrowing of the fabric the low part of the cam 124 at the right-hand side in Figure 4 finds its useful function in that it brings the needle butts to the proper level for the action of the up-picks. For this reason the guard cam 124 is provided with low parts at each side of the cam 123 so as to bring the needles down immediately to an elevation at which the pickers can act to move the needles in widening and narrowing.

Stitch length control

The main cam shaft 127 is driven by a pawl engaging a coarse ratchet 128. The rotation of the shaft controls in the usual manner changes in speed by means of a cam 129 acting on a belt shifter 130. It also controls the yarn feeds by means of cams indicated at 131 and controls changes from rotary to reciprocating knitting by a cam indicated at 132 and co-acting mechanism as in the Hemphill patent above referred. At the left end of the shaft in Fig. 1 is shown a cam or drum 133 which acts on a pair of followers 134 to change the length of the stitches by raising and lowering the cam ring relatively to the needle cylin-

der. For a sharp control over the length of stitches to enable such length to be changed, e. g. in successive revolutions, the cam shaft is provided with a ratchet disk 135 (Fig. 1) having a short series of closely spaced teeth 136 (Figs. 1 and 5) these teeth being positioned for engagement by a pawl 137 which may be mounted on the same eccentric 84 as the pawl 83 or on a similarly located eccentric. The pawl 137 is always in engagement with the periphery of the disk 135 so that when the teeth 136 come into position to be engaged the cam shaft has moved one step for each rotation of the needle cylinder. This arrangement may be utilized for changing the length of stitches quickly as is desirable in transferring from plain to rib knitting. In the present instance the teeth are positioned to operate the cam shaft rapidly for changing the length of the stitch at the time of transfer from plain to rib knitting.

Yarn feeding

The machine is provided with the usual yarn fingers 138 operated from the pattern mechanism by means of levers 139, links 140 and levers 141 resting on the cams 131. The ring 46 (Fig. 18) is provided with a resilient yarn clamp 142, a hook 143 underneath which the yarn passes, and a shear having a stationary blade 144 and a movable blade 145. The shear is operated by a plunger 146 (Fig. 19) here shown as provided with a roller at the top for engagement with a cam 147 (Fig. 19) at the underside of the gear 34. A link 148 connects the plunger to the movable shear blade. A yarn pusher 149 is pivotally supported on the bracket 30 and is moved in one direction by a cam 151 on the gear 34 against the tension of a spring 151'. The pusher has a notch at its forward end for engagement with a yarn that is moved into idle position and it is moved by a cam 151 in a manner to pick up an intermediate part of a yarn extending from an idle yarn-finger about the edge of the dial to the knitted fabric and to carry such a yarn into a position underneath the clamp 142 and into the space between the shear blades, as illustrated in Fig. 18. It will be understood that when the cam 151 releases the pusher it will move toward the back of the machine sufficiently far to pick up the next yarn moved up out of knitting position. The pusher swings back and forth at each rotation of the machine, but acts only on idle yarns, as the yarn which is being fed to the needles lies below the path of the pusher.

Take-up mechanism

The take-up mechanism (Figs. 1, 10 and 11) for this machine is secured to the lower end of the needle cylinder to rotate therewith and comprises a frame member 152 fixed to the usual ring gear (not shown) in any convenient manner. This frame member is open

at the sides and is provided with bearings for a pair of rollers 153 and 154, the first one of which is concave and the other convex. The rollers are connected at one end by suitable 5 gearing to cause them to rotate together. At the other end the roller 153 is provided with a gear 155 meshing with a gear 156 which in turn is driven by a gear on the same shaft with a ratchet 157 or integral with the ratchet. The ratchet is operated by a pawl 158 on a pawl lever 159 and is held in adjustable position by means of a pair of pawls 160 set so as to have their points spaced by one half the distance between two 10 teeth of the ratchet so as to reduce backlash. A spring 161 normally holds the lever against a stop 162 on the downwardly projecting part of the take-up frame and the spring is attached at one end to an adjusting screw 163 through an opening in a bent arm of a depending bracket 164, said screw carrying a nut 165 by which the tension of the spring may be adjusted.

The lever 159 has a downwardly projecting arm 166 positioned to engage with an abutment 167 (Figs. 10 and 12) at each rotation of the needle cylinder when the parts are in the position indicated in Fig. 12. The disc 133 on the pattern drum has cams at 169 25 for lifting the lever 170 pivoted at 171. This lever has attached thereto at its other end a rod 172 carrying the abutment 167 said rod being slidably mounted in a guide 173. A spring 174 attached at one end to a projection 30 174' tends to bring the abutment 167 into the position indicated in Fig. 12 which is the correct position for actuating the take-up during round-and-round knitting. When the pouches such as heels and toes of stockings 35 are being formed the cam shaft 127 is turned so as to bring the cams 169 under the end of lever 170 and pull the abutment 167 down below the position at which it can engage the pawl lever 159. The take-up therefore does 40 not act on the fabric during the formation of pouches, i. e. during reciprocating knitting.

Operation

In a typical operation of the machine of my invention for knitting a stocking the needle cylinder revolves and the cylinder needles are operated to knit a looper's margin of plain fabric. At this time the dial, of course, rotates with the cylinder but the dial cam cap and related parts are in the circumferential position illustrated in Figure 18 so that the needle wave is in a position where the needles will not take yarn. After a suitable length of material has been knitted the motion of the machine is changed to reciprocating for knitting the toe pocket, an additional yarn being put into action as usual throughout the toe. It will be recalled that during the formation of these pockets the take-up rollers are not operated, the lever

170 at this time being lifted by one or the other of the cams 169 to bring the abutment 167 out of reach of the pawl lever 159. The foot and heel are also made in usual manner and a short distance above the heel is formed as plain fabric. The incidental operations such as change of stitch length, etc. up to this time have been as in conventional manufacture of hosiery on a circular knitting machine.

The knitting is now to be changed from plain to ribbed for the production of a ribbed leg. As soon as the ankle portion has been knitted the travel of the pattern chain is changed from the normal 1×4 to 1×1 , i. e. instead of moving the chain one step to four revolutions of the cylinder it now is moved one step to each revolution of the cylinder, and a lug of the proper height on the right hand side of the pattern chain causes the dial cam to move from its idle position (Fig. 16) to the latch opening position (Fig. 15). The needle latches are opened by a brush 57' (Fig. 15). While the dial needles will be projected to their most outward position at this time the needle wave of the dial needles is far enough circumferentially from the knitting position to prevent the dial needles from taking yarn. It may be noted that all lugs on the pattern chain controlling the positions of the dial cam are at the right-hand side of the chain whereas the lugs for controlling the other operations of the machine are at the left-hand side. The dial needles remain in this position for as many revolutions as are required for opening the latches, the dial cam is then caused to rotate toward the knitting position (Fig. 13) and the cam track in plate 41 just above the dial cam which is stationary causes the dial needle projecting cam 62 to move to the half-way position (Fig. 14). The dial needles will now be in the first yarn taking position which is the tucking position of the needles. In other words the rotating of the cam from the latch-opening position toward the knitting position causes the dial needles to move to their half-way-in position and also to take their first course of yarn at the same time.

The positions of the follower 42 corresponding to the different phases of the knitting operation and to the positions of the needle projecting cam shown in Figures 13 to 16 are illustrated in Fig. 18. When the pin is in the position indicated at *a* the projecting cam is in idle position (Fig. 16) and the cam cap has been turned to the limit of its movement in a clockwise direction, viewed from above. When the cam cap is now moved counterclockwise to move the follower from position *a* to position *b* the parts assume the latch-opening position illustrated in Figure 15. The next movement in the same direction carries the follower from position *b* to position *c* which is the tucking position 130

where the yarn will now be taken and held by the hooks of the needles.

After the dial needles have taken one course of yarn a lug of the proper height causes the dial cam to rotate away from the knitting position, the projecting cam remaining in the half-way position in order to hold the loops of the first course, the follower being now in position *c*. This movement serves to prevent the dial needles from taking any more yarn for the next one or more revolutions as may be required. These courses of plain knitting serve to close up the large holes that would otherwise be made in the transfer. The next step in the operation is to turn the dial cam cap to bring the cam 62 into the knitting position (Fig. 13), the follower now being at *e*. It should be noted that the idle position of the follower at *a* is at the same distance from the axis of the machine as are the positions *c* and *d*. Similarly the follower and the cam are at the same distances from the axis in positions *b* and *e* of the follower. It should be remarked also that when the follower is in position *c* the needles are in tucking position but cannot take yarn because the needle wave has not been moved sufficiently far about the machine in a counterclockwise direction whereas when it has been advanced far enough to bring the follower to position *d* yarn will be taken. In moving in the contrary direction from *e* to *c* loops already on the needles will be held in either position *d* or position *c* of the follower. Finally position *b* is both the latch-opening position and the casting-off position so far as the follower and the needle projecting cam are concerned. It is to be understood that while making the transfer the pattern chain was traveling one step to each revolution of the cylinder and when the transfer is completed the travel of the pattern chain is changed back to one step of the chain to four revolutions of the cylinder.

It is desirable to give the stocking a finish by making what are called welts. These may be made in the following manner. First the travel of the pattern chain is changed from 1×4 to 1×1 . A lug of the proper height on this pattern chain causes the dial cam cap to rotate away from the knitting position causing the projecting cam to move to the half-way position (Fig. 14), the follower being at *d*. The dial needles will still receive yarn but the old loops will not knit off. The dial cam may be held in this position for as many courses as is wanted, after which it moves to *c*, the position of the cam remaining as before, but the dial needles ceasing to take yarn. Plain courses are now knitted as far as necessary according to the style of welt desired. The dial cam is then caused to rotate back to the knitting position thereby allowing the old loops to be knitted off. As many of these welts can be made as required.

After the welts have been made the dial cam is caused to rotate away from the knitting position and to the cast-off position which is the same as the latch-opening position. When the loops have been cast off from the dial needles the dial cam is rotated still further away from the knitting position to its idle position. The travel of the pattern chain is now changed from 1×1 to 1×4 . The machine is now ready to begin a new stocking.

It will be obvious to those skilled in the art that various changes may be made in my device without departing from the spirit of the invention and therefore I do not limit myself to what is shown in the drawings and described in the specification but only as indicated in the appended claims.

Figure 20 illustrates one such change. The yarn pusher 149' is pivoted on a bracket 150' similar to that shown in Figures 18 and 19, the yarn pusher, however, being smaller in form than that in the other figures. Whereas the yarn pusher 149 is nearly S-shaped, that of Figure 20 approaches more nearly to a straight line, the upper leg being approximately in line with the notched lower end. This form is preferable in some instances as being of smaller construction and less liable to get out of order.

Having thus fully described my said invention, what I claim as new and desire to secure by Letters Patent, is:

1. A knitting machine comprising dial and cylinder needles, a rotary needle cylinder, a rotary dial, needle actuating cams, pattern mechanism for controlling said cams to knit either ribbed, plain circular or reciprocating work as desired, yarn feeding means including a plurality of yarn-fingers, pattern mechanism controlling selectively the operation of said yarn-fingers, yarn-severing means on the dial cam cap, a cam moving in timed relation with the dial, and connections from said cam for operating said severing means, substantially as set forth.

2. A knitting machine comprising dial and cylinder needles, a rotary needle cylinder, a rotary dial, needle actuating cams, pattern mechanism for controlling said cams to knit either ribbed, plain circular or reciprocating work as desired, yarn feeding means including a plurality of yarn-fingers, pattern mechanism controlling selectively the operation of said yarn-fingers, yarn-severing means on the dial cam cap, a cam moving in timed relation with the dial, connections from said cam for operating said severing means, and means at one side of the severing means for guiding an idle yarn into said means, substantially as set forth.

3. A knitting machine comprising dial and cylinder needles, a rotary needle cylinder, a rotary dial, needle actuating cams, pattern mechanism for controlling said cams to knit

either ribbed, plain circular or reciprocating work as desired, yarn feeding means including a plurality of yarn-fingers, pattern mechanism controlling selectively the operation of said yarn-fingers, yarn-severing means on the dial cam cap, a cam moving in timed relation with the dial, connections from said cam for operating said severing means, means at one side of the severing means for guiding an idle yarn into said means, and means at the other side for clamping the yarn, substantially as set forth.

4. A knitting machine comprising dial and cylinder needles, a rotary needle cylinder, a rotary dial, needle actuating cams, pattern mechanism for controlling said cams to knit either ribbed, plain circular or reciprocating work as desired, yarn feeding means including a plurality of yarn-fingers, pattern mechanism controlling selectively the operation of said yarn-fingers, yarn-severing means on the dial cam cap, a cam moving in timed relation with the dial, connections from said cam for operating said severing means, and means for moving an idle yarn positively into reach of said severing means, substantially as set forth.

5. A knitting machine comprising dial and cylinder needles, a rotary needle cylinder, a rotary dial, needle actuating cams, pattern mechanism for controlling said cams to knit either ribbed, plain circular or reciprocating work as desired, yarn feeding means including a plurality of yarn-fingers, pattern mechanism controlling selectively the operation of said yarn-fingers, yarn-severing means on the dial cam cap, a cam moving in timed relation with the dial, connections from said cam for operating said severing means, a yarn-pusher, and a cam rotating in timed relation with said dial said cam operating said yarn-pusher, substantially as set forth.

6. A knitting machine comprising dial and cylinder needles, a rotary needle cylinder, a rotary dial, needle actuating cams, pattern mechanism for controlling said cams to knit either ribbed, plain circular or reciprocating work as desired, a take-up, and means for rendering the take-up inoperative during reciprocating work, substantially as set forth.

7. A knitting machine comprising dial and cylinder needles, a rotary needle cylinder, a rotary dial, needle actuating cams, pattern mechanism for controlling said cams to knit either ribbed, plain circular or reciprocating work as desired, a take-up rotating with the cylinder said take-up including a fabric contacting surface, a pawl and ratchet for moving said surface said pawl and ratchet rotating with the take-up, a stationarily mounted abutment, and pattern mechanism for moving said abutment into and out of the path of said pawl, substantially as set forth.

8. A knitting machine comprising dial and cylinder needles, a rotary needle cylinder, a rotary dial, needle actuating cams, pattern mechanism for controlling said cams to knit either ribbed, plain circular or reciprocating work as desired, connections from said pattern mechanism to a dial needle cam including an oscillatory cam cap, a fixed cam above said cam cap, and a follower on said needle cam engaging said fixed cam, substantially as set forth.

9. A knitting machine comprising dial and cylinder needles, a rotary needle cylinder, a rotary dial, needle actuating cams, pattern mechanism for controlling said cams to knit either ribbed, plain circular or reciprocating work as desired, connections from said pattern mechanism to a dial needle cam including an oscillatory cam cap, a fixed cam above said cam cap, and a follower on said needle cam engaging said fixed cam said cam cap being movable to a position wherein its needle cam causes the dial needles to cast off their stitches, substantially as set forth.

10. A knitting machine comprising a dial and cylinder needles, a rotary needle cylinder, a rotary dial, needle actuating cams, pattern mechanism for controlling said cams to knit either ribbed, plain circular or reciprocating work as desired, connections from said pattern mechanism to a dial needle cam including an oscillatory cam cap, a fixed cam above said cam cap, a follower on said needle cam engaging said fixed cam, and means for locking the cam cap in one position, substantially as set forth.

11. A knitting machine comprising dial and cylinder needles, a rotary needle cylinder, a rotary dial, needle actuating cams, pattern mechanism for controlling said cams to knit either ribbed, plain circular or reciprocating work as desired, connections from said pattern mechanism to a dial needle cam including an oscillatory cam cap, a fixed cam above said cam cap, a follower on said needle cam engaging said fixed cam, yielding means for moving the cam cap in one direction, and means for locking it against such movement, substantially as set forth.

12. A knitting machine comprising dial and cylinder needles, a rotary needle cylinder, a rotary dial, needle actuating cams, pattern mechanism for controlling said cams to knit either ribbed, plain circular or reciprocating work as desired, connections from said pattern mechanism to a dial needle cam including an oscillatory cam cap, and means for moving said dial needle cam in and out as the cam cap oscillates, substantially as set forth.

13. A knitting machine comprising dial and cylinder needles, a rotary needle cylinder, a rotary dial, needle actuating cams, pattern mechanism for controlling said cams to knit either ribbed, plain circular or reciprocating

work as desired, connections from said pattern mechanism to a dial needle cam including an oscillatory cam cap, a ring above said cap, means for holding said ring against oscillatory movement, and yarn-severing means on the ring, substantially as set forth.

5 14. A knitting machine as in claim 13, with means on said ring for holding the ends of idle yarns, substantially as set forth.

10 15. A knitting machine comprising dial and cylinder needles, a rotary needle cylinder, a rotary dial, needle actuating cams, pattern mechanism for controlling said cams to knit either ribbed, plain circular or reciprocating

15 work as desired, connections from said pattern mechanism to a dial needle cam including an oscillatory cam cap, a plate above said cam cap, lost-motion means for holding said plate against oscillatory movement, yarn-

20 changing means on the machine frame, yarn severing means on said plate, and means for moving said dial needle cam in and out as the cam cap oscillates, substantially as set forth.

25 In witness whereof I have hereunto set my hand and seal at Washington, District of Columbia, this twenty-first day of October, A. D. nineteen hundred and twenty-five.

WILLIAM L. SMITH, JR.
